HATSUNOSUKE YAMAMOTO, OF HIROSHIMA-SHI, HIROSHIMA-KEN, JAPAN.

OIL SEPARATOR.

Application filed November 22, 1927. Serial No. 235,108.

This invention relates to an oil separator adapted to remove from the exhaust steam of steam engines the oil contained therein and has for its object to provide an improved apparatus of this character.

The invention comprises a series of separating cylinders of corrugated cross section with a prefixed conoidal passageway respectively, whereby the separation of the oil from the exhaust steam is effected on the way through the said separating cylinders and the oil is ejected into the casing enclosing the said separating cylinders with drainage through a number of the small orifices provided at the prominent points or peaks of the corrugations of the said separating cylinders for that purpose, by the pressure of the exhaust steam.

The invention is illustrated in the accompanying drawings, in which:—

Fig. 1 is a vertical sectional view of an oil separator embodying the invention.

Fig. 2 is a cross sectional view on line II—II of Fig. 1.

Fig. 3 is a plan view of a separating cylinder, partly in section.

Fig. 4 is an end view thereof.

Fig. 5 is a plan view of a modification of the separating cylinder, partly in section.

Fig. 6 is a vertical sectional view of a modification of the oil separator.

Fig. 7 is a side view thereof.

Fig. 8 is a side view of a further modification of the oil separator.

Fig. 9 is a horizontal sectional view thereof.

Fig. 10 is a plan view of a further modification of the oil separator, partly in section.

Fig. 11 is an end view thereof, partly in section.

Fig. 12 is a sectional view on line XII—XII of Fig. 11.

Referring to the embodiment of the invention illustrated in Figs. 1 and 2 the casing 1 is of a cylindrical form, whilst its bottom or lower part forms a drain receiver 2 of a rectangular cross section, and is provided with legs 3 for mounting the device.

Within the casing 1 are arranged in series a number of the separating cylinders 5 which are of a corrugated cross section, in other words are longitudinally or obliquely corrugated as shown in Figs. 3, 4 and 5 and are provided with a number of small orifices 6 at every prominent point or peak of the corrugations, for ejecting the oil and drain separated from the exhaust steam passing through

the same. Around each separating cylinder an annular space 4 is provided, which communicates with the drain receiver 2 at the lower part.

Each of the separating cylinders 5 is disposed behind an inlet conical member 7 for directing the exhaust steam against the corrugated wall of the same, which consists of an outer wall 8 of frusto-conical form and an inner wall 9 of substantially conical shape connected together by the webs 10 or any other suitable means, and slightly projects into the said separating cylinder at its rear end.

The fore end cover 11 of the casing 1 is formed with an inlet branch 12 and an inlet annular cone for the foremost separating cylinder, whilst the rear end cover 13 is formed with an outlet branch 14.

Within the drain receiver 2 are arranged the division plates 15 for preventing the incoming oil and drain ejected from one of the separating cylinders 5 from splashing upon the other separating cylinders.

In operation, the exhaust steam flowing in the inlet branch 12 of the end cover 11 of the casing 1 in direction of the arrow from the steam engines, first will pass within the foremost conical separating cylinder through the foremost inlet member, striking against its corrugated wall, where a portion of the oil contained in the exhaust steam is separated therefrom and ejected to the drain receiver 2 through the orifices 6, at the peaks of the corrugations by the pressure of the exhaust steam, and will pass to the subsequent cylinder where the oil is separated and ejected in the similar manner and so on, and finally will pass to the outlet branch 14 of the rear end cover 13 of the casing 1.

The oil contained in the exhaust steam on the way of the exhaust steam from the inlet branch 12 to the outlet branch 14 will be separated with the drain by the separating cylinders and will stay in the drain receiver wherefrom the same will be drawn off by any suitable means through the drain cock 16.

In a modification illustrated in Figures 6 and 7, the separating cylinders 5 are arranged sectionally in series in a curved casing 17. In this case, the separating cylinder located in the curved part of the casing is spaced a suitable distance apart from separating cylinders located in the straight parts of the casing for reason of the construction, and the drain receiver of each section is connected

to the drain cock 16 by means of a drain pipe 18.

In a modification illustrated in Figs. 8 and 9, the separating cylinders 5 are arranged side by side in parallel but in opposite direction in two rows in a casing 19, a division plate 20 being provided between the rows of the separating cylinders, and the adjoining extremities of the two rows of the separating cylinders being in communication with each other by a junction box 21 formed at the end cover 22. The end cover 22 is also formed with an outlet 23 and a conical inlet member 7. The other end cover 24 is formed with an inlet branch 25, a conical inlet member 7 and an outlet branch 26. The exhaust steam of the steam engines will flow into a row of the separating cylinders through the inlet branch 25 and thence another row 20 through the junction box 21 and the inlet member 7, and finally will pass to the outlet branch 23 as indicated by the arrows.

In a modification illustrated in Figs. 10, 11 and 12, the separating cylinders 5 are arranged in three rows in a casing 27 of substantially triangular cross section, one row being centrally located upon the lower two rows located side by side. These rows are separated by division plates 28 and 29 provided within the casing. A pair of the adjoining extremities of the lower rows is communicated with each other by a junction box 30 formed in an end cover 31. The end cover 31 is also formed with an outlet 32, inlet member 7, and an outlet branch 33. At opposite side of the said junction box, the extremity of the upper row communicates with

the extremity of one of the lower rows by a junction box 34 formed in another end cover 35. The end cover 35 is also formed with an inlet branch 36, inlet member 7 and outlet 37. The exhaust steam from the steam engines will flow into one of the lower rows of the separating cylinders through the inlet branch 36 and inlet member 7, and thence into another lower row through the junction box 30 and conical inlet member 7 and thence upper row through the junction box 34 and conical inlet member 7 and finally pass to the outlet branch 33 as indicated by arrows.

Having now particularly described and ascertained the nature of my said invention and in what manner the same is to be performed, I declare that what I claim is:

1. An oil separator, comprising a casing having a drain receiver, a number of separating cylinders of corrugated cross section having a number of small orifices at every outwardly extending peak of the corrugations arranged in a series in the casing, a pair of conical members prefixed to every separating cylinder to form a conoidal inlet and division plates arranged in the drain receiver.

2. An oil separator, as set forth in claim 1, in which the separating cylinders are arranged in a series in a curved casing.

3. An oil separator, as set forth in claim 1, in which the separating cylinders are arranged in series in a casing in two rows side by side.

In testimony whereof I have signed my name to this specification.

HATSUNOSUKE YAMAMOTO.
